CONTROL BOX FOR AN ELECTRICAL APPLIANCE

Bert F. Strand, Jr., Toledo, Ohio, assignor to The Swartzbaugh Manufacturing Company, Toledo, Ohio, a corporation of Ohio

Application April 22, 1949, Serial No. 2,198

Term of patent 14 years

(Cl. D26—5)

To all whom it may concern:

Be it known that I, Bert F. Strand, Jr., a citizen of the United States, residing at Toledo, in the county of Lucas and State of Ohio, have invented a new, original, and ornamental Design for a Control Box for an Electrical Appliance, of which the following is a specification, reference being had to the accompanying drawings, forming a part thereof.

Figure I is a front view in perspective of a control box for an electrical appliance showing my new design.

Figure II is a rear perspective view of the design of the control box shown in Figure I.

Figure III is a fragmentary sectional view taken through the ribbed portion of the housing along the line indicated III—III in Figure I.

The dominant features of my design reside in the parts shown in full lines.

I claim:

The ornamental design for a control box for an electrical appliance, as shown and described.

BERT F. STRAND, JR.
